CLOTHESLINE PULLEY

Joseph Honore Horace Côté, Montreal, Quebec,
CanadaApplication March 12, 1936, Serial No. 68,507
In Canada May 27, 1935

3 Claims. (Cl. 254—197)

The present invention pertains to a novel clothes line pulley designed for hanging from a suitable support.

The principal objects of the invention are to provide an inexpensive and durable pulley as well as one that does not permit the line to run off the rotating wheel.

Accordingly, two wheel-like side pieces are mounted at opposite sides of the wheel and form loops across the rim of the wheel. These loops confine the line to the wheel rim. Further, they have each an expandable joint that permits large knots in the line to force themselves through rather than arrest movement of the line.

15 The parts are suspended by a shackle joined to the center of the wheel and side pieces by a single pivot pin. No other fastenings are required, so that the device is readily dismantled merely by removing this one member.

20 The invention is fully disclosed by way of example in the following description and in the accompanying drawing in which

Figure 1 is a side elevation of the pulley;

Figure 2 is a fragmentary plan view thereof;

25 Figure 3 is a detail section;

Figure 4 is a diametrical cross section; and

Figure 5 is a perspective view of one of the guards.

Reference to these views will now be made by 30 use of like characters that are employed to designate corresponding parts throughout.

The pulley wheel is indicated by the numeral 1 in Figure 4, and it will be seen that its rim 2 is grooved at 3 to retain the clothes line. The wheel 35 has a hub 4 at the ends of which are provided side pieces or guards as shown more clearly in Figures 1 and 5.

Each guard is a wheel-like member having spokes 5 and a circular rim 6. The rim is rabbed at 7 to receive an edge of the wheel rim 2, and has its inner surface curved at 8 in continuation of the groove 3. From opposite points of each guard extend semi-circular members 9 for a purpose presently to be described.

45 The members 9 of opposite guards join one another by means of a tongue 10 and groove 11 to form a slip joint. The guards are held to the pulley wheel 1 by a slip 12 enclosing the parts, all being held together by a pin 13. The outer 50 end of the shackle is formed as a loop 14 similar to the loops 9, 9. This end also has an eyelet 15 for suspension from a hook or nail in the usual manner.

The uses and advantages of the invention will 55 now be described. An inexpensive and durable

pulley is provided, inasmuch as the guards require no fastening rivets but merely the central pivot pin 13. The loops 9, 9 prevent the clothes line from running off the pulley in addition to the guiding action of the groove 3 and continued surfaces 8 thereof.

In this connection, the loops 9, 9 are also expandable at their slip joints 10, 11 to permit passage of large knots in the clothes line, so that such knots do not stop the line.

10 Further, the device is readily dismantled by removing the single pivot pin 13. Finally, the structure is considerably strengthened by the side pieces or guards.

15 Preferably, the side pieces have pairs of lugs 16 straddling the sides of the members 12 to prevent rotation of the side pieces and spacing pins 17 to prevent pressure on the pulley.

20 Although a specific embodiment of the invention has been illustrated and described it will be understood that various alterations in the details of construction may be made without departing from the scope of the invention as indicated by the appended claims.

25 What I claim is:—

1. A clothes line pulley comprising a wheel, circular side pieces at opposite sides of said wheel and adjacent to the rim of said wheel, and semi-circular extensions from said pieces, the extensions from each piece engaging those from the other piece to form loops over the rim of said wheel, the mutually engaging extensions having a slip connection with each other expandable along the width of the respective loop to permit enlargement thereof.

35 2. A clothes line pulley comprising a wheel, circular side pieces at opposite sides of said wheel, and semi-circular extensions from said pieces, the extensions from each piece engaging those from the other piece to form loops over the rim 40 of said wheel, said rim having a running groove and the internal diameter of said loops being several times greater than that of said rim, the mutually engaging extensions having a slip connection with each other expandable along the 45 width of the respective loop to permit enlargement thereof, the rim of said wheel having a rope groove, said side pieces overhanging said rim and having surfaces in continuation of said groove.

3. A clothes line pulley comprising a wheel, circular side pieces at opposite sides of said wheel, and semi-circular extensions from said pieces, the extensions from each piece engaging those from the other piece to form loops over the rim of said wheel, said rim having a running groove and the 55

internal diameter of said loops being several times greater than that of said rim, the mutually engaging extensions having a slip connection with each other expandible along the width of the respective loop to permit enlargement thereof, the rim of said wheel having a rope groove, said side pieces overhanging said rim and having surfaces

in continuation of said groove, a shackle straddling said wheel and side pieces, a pivot pin passed through said shackle and the centers of said wheel and pieces, the outer end of said shackle forming a loop similar to the first named loops.

JOSEPH HONORE HORACE CÔTÉ.
